TABLE

Stanley J. Malec, Leoneth, Minn.

Application July 27, 1953, Serial No. 26,150

Term of patent 3½ years

(Cl. D33—14)

To all whom it may concern:

Be it known that I, Stanley J. Malec, a citizen of the United States, residing at Leoneth, in the county of St. Louis and State of Minnesota, have invented a new, original, and ornamental Design for a Table, of which the following is a specification, reference being had to the accompanying drawing, forming part thereof.

The single drawing figure is a perspective view of a table, showing my new design.

The dominant features of my design reside in the portions shown by full lines.

I claim:

The ornamental design for a table, as shown and described.

STANLEY J. MALEC.
